UNITED STATES PATENT OFFICE

167,718

COMBINED WALL PLAQUE AND PIN-UP LAMP

Leo Rabkin, New York, N. Y.

Application February 29, 1952, Serial No. 18,722

Term of patent 3½ years

(Cl. D48—4)

To all whom it may concern:

Be it known that I, Leo Rabkin, a citizen of the United States of America, residing in the Borough of Queens, city and State of New York, have invented a new, original, and ornamental Design for a Combined Wall Plaque and Pin-Up Lamp, of which the following is a specification, reference being had to the accompanying drawings, forming part thereof, wherein—

Figure 1 is a front elevational view of a combined wall plaque and pin-up lamp, showing my new design.

Fig. 2 is a top plan view thereof, partly broken away and with the lamp shade and light bulb omitted.

Fig. 3 is a side elevation as viewed from the right hand side of Fig. 1, with the lamp shade and light bulb omitted.

The characteristic features of the design reside in the solid line portions.

I claim:

The ornamental design for a combined wall plaque and pin-up lamp, as shown and described.

LEO RABKIN.
